UNITED STATES PATENT OFFICE.

HENRY CULL, OF CHICAGO, ILLINOIS.

ROAD-ROLLER.

1,320,533.

Specification of Letters Patent.

Patented Nov. 4, 1919.

Application filed April 9, 1917. Serial No. 160,689.

To all whom it may concern:

Be it known that I, HENRY CULL, a citizen of the United States, and a resident of the city of Chicago, in the county of Cook and State of Illinois, have invented certain new and useful Improvements in Road-Rollers; and I do hereby declare that the following is a full, clear, and exact description of the same, reference being had to the accompanying drawings, and to the numerals of reference marked thereon, which form a part of this specification.

In the ordinary type of road-rollers wherein a single cylindrical roller is used, or where a number of rollers are used, all mounted upon a single axle, unsatisfactory results have been obtained due to the fact that on roads under construction or repairs where materials have been deposited in small scattered heaps and left to be smoothed down or leveled by manual labor or spreaders, the lower portions of the material heaps are always packed or compressed, due to the dumping process and the weight of the upper portions of the heaps, to a greater extent than the portions of the road between the heaps which have been filled by the spreading process with loose materials. When the old type of road-rollers are run over the road, the roller or rollers only contact the lower already partly packed portions of the material heaps, thus still further compressing or packing the same, but usually failing to contact or bear upon the loose material portions, thereby only partially rolling the road and leaving weak unpacked portions in the road which later on are the first to give way.

This invention relates to an improved form of road-roller wherein a plurality of comparatively narrow roller wheels are arranged in staggered relation to one another, and each individually mounted and separately supported by an adjustably weighted frame, the inner end of which is pivotally connected to the fore-part or turn-table of the road-roller to permit each roller wheel to either raise or lower as the road-roller is drawn over a rough or unpacked road, so that all portions of the road will be packed or compressed uniformly, thereby showing up the portions requiring more filling in, and thus producing a roadbed which is solid and properly packed throughout.

It is an object of this invention to construct an improved form of road-roller

adapted to pack all portions of a roadbed equally.

It is also an object of this invention to provide a road-roller having a plurality of 60 adjustable individually mounted weighted packing rollers, affording a means for uniformly packing a roadbed.

It is a further object of this invention to construct a road-roller wherein weighted 65 hingedly mounted individual supports are provided for staggered rollers, to afford a means for packing all parts of a road bed uniformly.

It is furthermore an object of this invention to construct a road-roller adapted to be removably connected to a cart or propelling vehicle, and comprising a plurality of hingedly mounted supports of different 75 lengths for packing rollers, each support provided with adjustably mounted weights to afford a means of varying the pressure applied by said rollers.

It is an important object of this invention to provide a road-roller simple and of effective 80 construction wherein a plurality of adjustable individually mounted staggered weighted rollers are connected to a common propelling means, to afford a means for uniformly packing all parts of an uneven road- 85 bed.

Other and further important objects of the invention will be apparent from the disclosures in the drawings and specification.

The invention (in a preferred form) is 90 illustrated in the drawings, and hereinafter more fully described.

On the drawings:

Figure 1 is a top plan view of a road-roller embodying the principles of this in- 95 vention.

Fig. 2 is a side view thereof with parts broken away.

Fig. 3 is a rear end view of the device.

Fig. 4 is a section taken on line 4—4, of 100 Fig. 1.

Fig. 5 is a section taken on line 5—5 of Fig. 1.

Fig. 6 is an end view thereof.

As shown on the drawings:

The reference numeral 1, indicates the wheels of a fore carriage, cart or vehicle, rotatably mounted upon the ends of an axle 2, supported by an axle bar 3, having centrally mounted thereon an anvil support 4, 110 to which is secured by any suitable means a shaft or tongue 5, to permit the cart to be

attached to a motor vehicle or be drawn by horses as desired. Pivotsly mounted upon the anvil support 4, by means of a kingbolt or pin 6, and a reinforcing plate or block 5 7, is a cross-beam or channel iron 8, to which said block 7, is rigidly secured centrally therein between the front flange 9, and the rear flange 10, by rivets or any other suitable means.

10 A plurality of transversely adjustable hinges are disposed adjacent one another across the rear flange 10, of the channel iron 8, and each comprises an apertured yoked upper hinge member 11, having an 15 integral hook 12, thereon adapted to engage over the upper edge of the flange 10, to permit an integral apertured attaching flange 13, forming a part of said upper hinge member 11, to lie flat against the 20 under surface of said channel iron 8, and be rigidly secured thereto by means of screw bolts 14, as clearly shown in Fig. 6. Pivotsly connected to each of the upper hinge members 11, by means of a pintle 15, is a 25 lower hinge member 16, having an apertured ear or lug 17, integrally formed centrally on the upper surface thereof adapted to engage between the forks of said yoked upper hinge member to permit the pintle 30 15, to project through the apertured forks and through said apertured lug 17, to form a hinge.

Rigidly but removably secured by means of a retaining bolt 18, in a suitable longitudinal T-shaped slot 19, formed in each 35 of said lower hinge members 16, is a rearwardly extending supporting I-beam 20. The I-beams 20, are of different lengths, preferably two, alternately arranged with 40 respect to one another across the rear of the propelling cart, as clearly shown in Fig. 1. Adjustably secured by means of bolts 21, to the outer or rear end of each of said supporting beams 20, and slidably engaging 45 the upper flange thereof is a weight 22, provided with a longitudinal T-slot 23, in the lower portion thereof to permit said sliding engagement.

A double armed or yoked axle support 24, 50 having an inverted T-slot 25, formed in the upper end thereof, is slidably engaged upon the outer or rear end of the lower flange of each I-beam 20, and removably secured in an adjusted position upon said lower flange by retaining bolts 26, which are threaded through the upper portion of the axle support to grip or engage the lower I-beam flange. Integrally formed on the lower end of each of the forks or arms of 55 each axle support 24, is a cylindrical hub or bearing rim 27, in each pair of which is journaled a stub axle 28, on which is keyed or otherwise secured between the arms of each axle support 24, a heavy roller or 60 65 wheel 29, the outer rim of which is com-

paratively wide and flat to afford a suitable bearing surface to contact or roll upon the surface of an uneven or rough roadbed 30, upon which the road-roller is operating to uniformly pack or level the same. From the description of the roller mechanisms, it will be seen that the rollers 29, are arranged in staggered relation across the device due to the arrangement of the short and long hingedly mounted supporting I-beams 20. 75

The operation is as follows:

With the road-roller parts arranged as shown and described a team of horses may be hitched to the cart tongue 5, or said tongue may be attached to the rear of any 80 suitable type of motor vehicle to afford a means for drawing the road-roller over an uneven roadbed 30. As the road-roller is propelled or drawn along the adjustable weights 22, secured in position upon the 85 supporting I-beams 20, together with the weights of said I-beams and the rollers 29, tend to force or press the respective staggered rollers 29, tightly down upon the roadbed, thus uniformly compressing or 90 packing all parts of said roadbed coming in contact with said adjustable road-roller. With each of the rollers 29, rotatably connected to one of the hingedly mounted I-beams 20, it will be seen that an adjustable 95 road-roller is produced which is adapted to be drawn over any uneven or rough roadbed and so adjust itself that the staggered rollers 29, may either be raised or lowered automatically to conform to the surface 100 over which they are being drawn to compress or pack all parts of the roadbed uniformly, and indicating which portions require additional filling in to make the entire roadbed of an even thickness and packed 105 uniformly throughout, thus eliminating any weak spots in the roadbed, which usually occur when road-rollers are used in which the rollers are extremely wide and are mounted upon the same axle. 110

As clearly shown in Fig. 1 of the drawings, it will be noted that the roller carriage or rear portion of the road-roller is pivotsly connected to the fore carriage by means of the kingbolt 6, thus permitting 115 the device to be turned as desired. It is also apparent that the fore carriage may be dispensed with and that the kingbolt 6, may be replaced by a suitable hook member to afford a means of connecting the roller portion of the device to the rear axle of any suitable form of drawing vehicle.

It will be noted that in order to uniformly pack all parts of the roadbed over which the road-roller is drawn, it has been 125 found necessary, under the construction shown, to arrange the rollers 29, in staggered relation to one another across the device. This arrangement is accomplished by providing the short and long hingedly 130

mounted supporting I-beams 20, or other suitable mounting means, which afford the supports for the rollers. It will of course be understood that the adjustable roller mechanism may be formed by arranging the road rollers closely adjacent one another across the device in a single row, or in any number of rows desired to accomplish the purpose of uniformly packing a roadbed.

I am aware that various other details of construction may be varied through a wide range without departing from the principles of this invention, and I therefore do not purpose limiting the patent granted otherwise than necessitated by the prior art.

I claim as my invention:

1. A road-roller comprising a supporting means, and a plurality of rollers each independently adjustable longitudinally and transversely on said supporting means.

2. In a road-roller of the class described, a fore carriage, and a plurality of staggered rolling means hingedly connected therewith and adjustable longitudinally of the machine.

3. In a road-roller of the class described, a fore carriage, members pivotally connected therewith, a plurality of rollers, one rotatably connected with each member, and adjustable longitudinally thereof.

4. In a road-roller of the class described, a fore carriage, a channel member pivotally mounted thereon, a plurality of bars pivoted to the channel member, a roller slidably engaged to each bar and a weight adjustably secured to each bar.

5. In a road-roller of the class described, a fore carriage, a plurality of supporting means of different lengths hingedly connected therewith, and a roller on each of said supporting means adjustable longitudinally thereof.

6. A road-roller comprising a carriage, a beam pivotally mounted thereon, a plurality of bars hinged to said beam, a roller on each bar adjustable longitudinally thereon, and a weight on each bar adjustable longitudinally thereof.

7. In a device of the class described, a fore carriage, a cross-beam movably mounted thereon, a plurality of adjacently disposed hinges secured thereto, supporting means of different lengths removably secured to said hinges, weights adjustably mounted thereon, and rolling means adjustably connected to said supporting means in staggered relation to one another.

8. In a device of the class described, a fore carriage, and a plurality of individ-

ually mounted longitudinally adjustable rollers and weights, said rollers and weights being independently adjustable.

9. In a road roller a carriage, a channel bar pivoted thereto, hinge members, each provided with a hook to engage one flange of said channel member, a plurality of I beams, one secured to each hinge, a roller adjustably secured to the lower flange of each I beam and a weight adjustably secured to the upper flange of each I beam.

10. In a road-roller of the class described, a fore carriage, connecting means pivotally mounted thereon, hinges secured thereto, supporting members of different lengths secured to said hinges, weights adjustably mounted upon said supporting members, and roller means adjustably mounted upon said supporting members.

11. In a device of the class described, an axle, a pair of wheels journaled thereto, a bolster pivoted to the axle, a plurality of members hinged to the bolster and extending rearwardly therefrom, a roller wheel journaled to each member, and means for varying the pressure of each roller wheel.

12. In a rolling device of the class described, the combination of a plurality of transversely adjustable longitudinal members pivoted at their forward ends so as to be independently movable, and a roller longitudinally adjustable under the free end of each longitudinal member.

13. In a device of the class described, the combination of a plurality of members pivoted at their forward ends so as to be independently movable, a bracket depending from the free end of each member and longitudinally adjustable thereon, and a roller mounted in each bracket below the respective member.

14. In a rolling device of the class described, the combination of a plurality of longitudinal members pivoted at their forward ends so as to be independently movable, a roller mounted under the free end of each longitudinal member for independently supporting the said member, a bearing depending from each longitudinal member for connecting the roller therewith, the said bearings being arranged in staggered relation to permit close positioning of the adjacent rollers.

In testimony whereof I have hereunto subscribed my name in the presence of two subscribing witnesses.

HENRY CULL.
